UNITED STATES PATENT OFFICE.

CHARLES F. SMITH, OF NEW BRITAIN, CONNECTICUT.

DESIGN FOR CUTLERY HANDLE-TIPS.

SPECIFICATION forming part of Design No. 20,116, dated August 26, 1890.

Application filed July 28, 1890. Serial No. 360,223. Term of patent 7 years.

To all whom it may concern:

Be it known that I, CHARLES F. SMITH, a citizen of the United States, residing at New Britain, in the county of Hartford and State 5 of Connecticut, have invented and produced a new and original Design for Cutlery Handle-Tips, of which the following is a specification, reference being had to the accompanying drawing, in which the only figure is a side 10 elevation of a knife and handle showing my design.

The leading feature of my design consists in the ornamental tips at the respective ends of the handle.

15 *a* designates the tip at the shank or bolster end of the handle; *b*, the tip at the opposite end, and *c* the body of the handle, which is of the usual oval form and tapers toward what is usually termed the "butt-end," although 20 in the present instance said end is the smaller.

The tip *a* consists mainly of a short tapering portion 1 and a beaded portion 2, the surfaces of which portions are ornamented with scroll figures, as shown. The parts 1 and 2 25 are divided by a narrow band, and there is a narrow band at each end.

The tip *b* has a band 3 at its largest end, which joins the handle-body, and the contour or outline of said tip is in the form of a horn. Its sides are ornamented with scroll figures, 30 as shown, the outer scroll figures being nearly parallel with the upper edge of the tip and extending nearly its whole length.

What I claim is—

1. The design for handle-tips herein shown 35 and described, the same comprising the tip *a*, with its tapering and beaded portion having scroll ornaments, and the tip *b*, horn-shaped in side view and having the scroll ornamentation, as set forth.

2. In the design for knife-handle tips herein shown and described, the tip *a*, having the tapering and beaded portion with scroll ornamentation, as set forth. 40

3. In the design for the knife-handle tips 45 herein shown and described, the tip *b*, horn-shaped in side view and having the scroll ornaments, as set forth.

CHARLES F. SMITH.
